UNITED STATES PATENT OFFICE.

FRED W. A. TECHMER, OF LA CROSSE, WISCONSIN.

PLOW.

1,274,815.

Specification of Letters Patent. Patented Aug. 6, 1918.

Application filed September 17, 1913. Serial No. 790,152.

To all whom it may concern:

Be it known that I, FRED W. A. TECHMER, a resident of La Crosse, in the county of La Crosse and State of Wisconsin, have invented certain new and useful Improvements in Plows, of which the following is a full, clear, and exact description.

The invention relates to plows and has for its purpose to provide simple and efficient means whereby the plowshare may be detached from or readily and firmly secured to the landside and moldboard of the plow.

The invention consists in the several novel features hereinafter set forth and more particularly defined by claims at the conclusion hereof.

In the drawings: Figure 1 is an underneath perspective view of the plow. Fig. 2 is an inverted plan of the plow showing the parts connected together. Fig. 3 is a detail cross-section taken on line 3—3 of Fig. 1. Figs. 4 and 5 are detail views of the hook lever. Fig. 6 is a side elevation of the angular draw-bar. Fig. 7 is an inverted plan of said draw-bar. Fig. 8 is a sectional view of the angular draw-bar taken on line 8—8 of Fig. 7. Fig. 9 is a section taken on line 9—9 of Fig. 2. Fig. 10 is a section taken on line 10—10 of Fig. 2.

The plow comprises a moldboard 2, and a landside 1, both of which are fixedly secured to a frog or angle-plate 3, and a detachable plowshare 8 which is secured to the frog and to the moldboard by means herein-after set forth. The frog conforms to and fits against the back face of the moldboard and is secured thereto by bolts 2^b. The fixed landside 1 is secured to the side flange of the frog 3 by one or more bolts 2^a. The frog is secured to a plow-beam 30 by bolts 31 which extend through the side flange 3^d of the frog and the beam, and one of said bolts also secures a brace 5 which has its outer end secured to the moldboard by a bolt 7, to the beam. In this manner, the frog, landside, moldboard and beam are fixedly secured together.

The lower portion of the frog projects outwardly and downwardly beyond the lower edge of the moldboard to provide a seat conforming to the back face of the share. The upper edge of the plowshare is adapted to abut against the lower edge of the moldboard. The front portion of the plowshare comprises a side-portion 8^d, the back edge 8^b of which is adapted to abut

against the front edge of the landside 1. This side portion 8^d is formed with a notch 8^a to receive the lower front corner 1^a of the moldboard. The frog with its side-flange 3^d thus forms an angular face upon which the removable plowshare will be seated. When the removable plowshare is seated on the frog and notch 8^a on the share engages the corner of the moldboard 2 and the share is jammed against the outer or front face of the frog, the plowshare will have its upper surface flush with the moldboard and the side portion 8^d will be flush with the landside.

The lower portion of the frog projects outwardly and downwardly beyond the lower edge of the mold-board and this projecting portion is provided with upwardly and rearwardly inclined slots or notches 20. The point of the frog also projects forwardly of the moldboard and the fixed landside. These notches are adapted to receive keepers 9 which pass through and are secured to the plowshare. Each keeper 9 comprises a bolt 80 11 and a sleeve 12 having a tapered flange 13 which is locked in place by the nut 13^a. A similar sleeve 13 is secured to the plowshare rearwardly of the frog by a bolt 11^a. Notches 20, when the share is being attached, 85 guide the bolts and sleeves on the share to cause the share to move into operative position and so it will make joint with the mold-board and landside.

A bar 21 is provided with notches 23, 24, 90 adapted to fit around the sleeves 12 of the bolts 11, respectively, and a lever 14 which is pivoted to the moldboard by a bolt 16, has a notch 17 adapted to fit around the sleeve 13 of bolt 11^a. The notched ends of bar 21 and lever 14 serve as hooks for engaging the keepers on the plowshare, and said bar and lever serve as means for drawing the share upwardly and backwardly to cause the edges of the share to abut against the edges of the 100 moldboard and landside, respectively.

Bar 21 and lever 14 are adapted to be conjointly operated to draw the plowshare upwardly and backwardly by an eye-bolt 19. The eye of bolt 19 engages a bolt 22 which extends through an aperture 22^b in bar 21 and the other end of said bolt extends through a slot 18 in the upper and inner end of lever 14. Bar 21 is angled at its center so hole 22^b will be disposed for effective 110 draft by eye-bolt 19. A hole 22^c is provided in bar 21 for bolt 22, to adjust the distance

between the bar and lever 14, if necessary. A nut 25 adjacent the outer end of bolt 19, when turned in one direction, will force lever 14 around its pivot and will draw the 5 bar 21 upwardly and backwardly in the direction of the seat on the frog and thus draw the plowshare to form a joint between it and the moldboard and landside. By employing lever 14 acting upon a plurality of bolts 10 on the plowshare and lever 14 acting upon a third bolt on the plowshare a joint between the removable plowshare and moldboard and landside will be attained by means of a single device, such as the bolt 19, and the attaching-means may be disposed close to the frog. By means of bolt 19 all of the draw-means may be operated with great force to secure the plowshare.

In addition to providing for engagement 20 between the edges of the plowshare and the moldboard and landside, it is desirable in a detachable plowshare, to firmly seat it on the frog, so that the share will be rigid on the frog. For this purpose, bar 21 is provided 25 with beveled or wedge-surfaces 24^a around notches 23 and 24 and lever 14 is also provided with a wedge-surface 17^a around its notch 17. The wedge-surfaces on bar 21, when forced under the inclined flanges of 30 sleeves 13, respectively, cause the detachable plowshare to be jammed against its seat on the projecting portion of the frog. The wedge-surface on lever 14 jams the rear end 35 of the share against the outer face of said lever to secure the rear portion of the plowshare on lever 14, the lever being flush with the back face of the moldboard. This jamming action is effected by bolt 19 at the same 40 time that the bar 21 and lever 14 are operated to draw the edges of the plowshare into engagement with the edges of the moldboard and landside.

To detach the plow, it is only necessary to loosen nut 25 on the bolt 19 and then swing 45 the bolt out of notch 18 of lever 14, or the nut may be run back far enough on bolt 19 to permit the hook to be released from bolts 11, 11^a without swinging bolt 19 out of slot 18. Lever 14 and bar 21 will then be released so they can be disengaged from the 50 keepers on the plowshare.

The invention is not to be restricted to the details set forth, since these may be modified within the scope of the appended claims 55 without departing from the spirit and scope of the invention.

Having thus described my invention, what I claim as new, and desire to secure by Letters Patent, is:

60 1. In a plow, the combination with a landside, a moldboard, a detachable plowshare and a frog, of means for drawing the share upwardly and toward the moldboard to force the edge of the share against the edge 65 of the moldboard, comprising a bar, a

lever, devices on the share and wedging surfaces between said devices and the bar and lever to jam the share inwardly against the outer face of the frog, and a device for conjointly operating the lever and said bar. 70

2. In a plow, the combination of a landside, a moldboard, a detachable plowshare, and means for detachably securing the plowshare, comprising a lever pivoted to the moldboard, means on the share engaged by 75 the lever and a screw for operating the lever around its pivot.

3. In a plow, the combination of a landside, a moldboard, a detachable plowshare, and means for detachably securing the plowshare, comprising a lever pivoted to the moldboard, a screw for operating the lever around its pivot and a keeper on the share 80 engaged by said lever.

4. In a plow, the combination of a landside, a moldboard, a detachable plowshare, and means for detachably securing the plowshare, comprising a lever pivoted to the moldboard, a screw for operating the lever around its pivot and a keeper on the share 90 engaged by said lever, the lever having a hook at one end for engaging said keeper.

5. In a plow, the combination of a landside, a moldboard, a detachable plowshare, and means for detachably securing the share, 95 comprising a lever pivoted to the moldboard, a screw for operating the lever around its pivot, and removably connected to one end of said lever, and a keeper on the share engaged by said lever, the lever being provided 100 with a hook for engaging the keeper.

6. In a plow, the combination of a landside, a moldboard, a detachable plowshare, and means for detachably securing the plowshare comprising a plurality of keepers on 105 the share, devices adapted by opposing movement to engage and secure the keepers, and draw-means between said devices whereby they will be drawn together and secured in operative position. 110

7. In a plow, the combination of a landside, a moldboard, a detachable plowshare, and means for detachably securing the plowshare, comprising a lever pivoted to the moldboard, a keeper on the share and secured 115 by said lever, a draw-bar, a plurality of keepers on the share engaged by said draw-bar, said lever and bar being adapted by movement toward each other to secure the keepers, and means for drawing said lever and bar together to lock them in operative 120 position.

8. In a plow, the combination of a landside, a moldboard, a frog to which the landside and moldboard are secured, a detachable plowshare, the frog having a portion thereof projecting below the lower edge of the moldboard having slots in its projecting portion, a pair of keepers on the share adapted 125 to enter said slots, a draw-bar having inter- 130

gral hooks for engaging both of the keepers, and means for locking the draw bar.

9. In a plow, the combination of a landside, a moldboard, a frog to which the landside and moldboard are secured, a detachable plowshare, said frog having a portion thereof projecting below the lower edge of the moldboard and having slots in the projecting portion, a pair of keepers on the share adapted to enter said slots, a draw-bar having means for engaging both of the keepers, a lever pivoted to the moldboard, a keeper on the share engaged by the lever and locking-means between the draw-bar and the lever.

10. In a plow, the combination of a landside, a moldboard, a frog to which the landside and moldboard are secured, a detachable plowshare, a frog having a portion thereof projecting below the lower edge of the moldboard and having slots in the projecting portion, a pair of keepers on the share adapted to enter said slots, a draw-bar having means for engaging said plurality of keepers, a lever pivoted to the moldboard, a keeper on the share engaged by the lever and a bolt between the draw-bar and the lever for locking them in operative position.

11. In a plow, the combination with a landside, a moldboard, a frog having a plurality of notches at its lower edge, a detachable plowshare having a plurality of keepers

adapted to engage the notches of the frog, and means comprising an angular bar having hooks for engaging the keepers, and means for locking said bar.

12. In a plow, the combination of a landside, a moldboard, a frog having a plurality of notches at its lower edge, a detachable plowshare having keepers adapted to engage the notches of the frog, an angular bar having hooks engaging with the keepers and locking means including a bolt pivoted to the bar.

13. In a plow, the combination of a landside, a moldboard, a frog, a lever pivoted to said moldboard, a detachable plowshare having a plurality of keepers, one of which is adapted to be held by said lever, a bar engaging with the other keepers, and a locking bolt between the bar and the lever.

14. The combination of a moldboard, a landside, a frog, a detachable plowshare having a plurality of keepers mounted thereon, means for securing said detachable section, comprising a lever pivotally mounted on said moldboard, a draw-bar for engaging the keepers on the share, a clamping-bolt connected to said lever and an adjustable connection between the bolt and said bar.
